GRASS MOWER

Bernt Filip Valentin Holm, Teckomatorp, Sweden, assignor to Karl Sven Ingemar Svenningson, Anderstorp, Sweden

Filed Apr. 10, 1968, Ser. No. 11,403

Term of patent 14 years

Int. Cl. D15—03

U.S. Cl. D40—1

FIG.2

FIG.3

FIG. 1 is a side elevational view of a grass mower embodying the design;

FIG. 2 is a front view of the grass mower;

FIG. 3 is a back view of the grass mower; and

FIG. 4 is a top plan view of said mower.

The dominant features reside in the solid line portions.

What I claim is:

The ornamental design for a grass mower, as shown and described.
